Primary Examiner — Darlington Ly(74) *Attorney, Agent, or Firm* — JCIP Global Inc.(57) **CLAIM**

The ornamental design for a lithium-ion battery hammer drill, as shown and described.

DESCRIPTION

FIG. 1 is a perspective view of a lithium-ion battery hammer drill embodying our new design;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings represent the portions of the lithium-ion battery hammer drill that form no part of the claimed design.

1 Claim, 7 Drawing Sheets(56)
